REMOTE CONTROL TERMINAL

Donald Harry Wood, Santa Clara, and Donald Anthony Moore, Los Gatos, Calif., assignors to International Business Machines Corporation, Armonk, N.Y., a corporation of New York

Filed Aug. 9, 1966, Ser. No. 3,403

Term of patent 14 years

(Cl. D26—13)

FIG. 1

FIG. 2

FIGURE 1 being a front perspective view of a remote control terminal, showing our new design; and

FIGURE 2, drawn to a different scale than FIGURE 1, being a rear elevation view of said remote control terminal.

The essential features of our design reside in the portion shown in solid lines.

We claim:

The ornamental design for a remote control terminal, as shown and described.
